[57] CLAIM

The ornamental design for a paint pad, as shown and described.

DESCRIPTION

FIG. 1 is a perspective view of a paint pad embodying my new design;

FIG. 2 is a top plan view thereof shown on a slightly larger scale;

FIG. 3 is a side elevational view thereof with the paint pad rotated 180° with respect to the position in which it is shown in FIG. 2;

FIG. 4 is an end elevational view thereof; and

FIG. 5 is a bottom plan view thereof.

The bristles which cover the entire bottom surface of the paint pad have been omitted in FIG. 5 for ease of illustration.
